UNITED STATES PATENT OFFICE.

EDWARD RILEY, OF SPOKANE, WASHINGTON.

THREAD-CUTTING MACHINE.

1,072,503.

Specification of Letters Patent. Patented Sept. 9, 1913.

Application filed August 31, 1912. Serial No. 718,153.

To all whom it may concern:

Be it known that I, EDWARD RILEY, a citizen of the United States, residing at Spokane, in the county of Spokane and State 5 of Washington, have invented a new and useful Thread-Cutting Machine, of which the following is a specification.

This invention relates to thread cutting machines.

10 The primary object of the invention is to provide a machine of this character in which both ends of the stock may be threaded from a common drive, means being provided for forming either right or left hand threads 15 on either end of the stock.

A further object of the invention is to provide means for driving the cutting members by power or by hand.

A still further object of the invention is 20 to provide means for moving one of the heads longitudinally of the machine frame to accommodate various lengths of stock and to thread the same at various points.

Another object of the invention is to provide 25 means for feeding the other head a limited distance on the frame and locking the same against movement.

A further object of the invention is to provide 30 a driving mechanism for the cutting members in which the direction of either or both may be readily changed.

A still further object of the invention is to provide 35 a cutting member in which the dies may be readily brought into contact with the stock.

With the foregoing and other objects in view which will appear as the description proceeds, the invention resides in the combination and arrangement of parts and in the 40 details of construction hereinafter described and claimed, it being understood that changes in the precise embodiment of invention herein disclosed can be made within the scope of what is claimed without departing 45 from the spirit of the invention.

In the drawings: Figure 1 is a side elevation. Fig. 2 is a top plan view, the heads being removed. Fig. 3 is a transverse section showing the right hand head. Fig. 4 is 50 a transverse section showing the left hand head, which is disposed to move longitudinally of the machine frame. Fig. 5 is a transverse section of the heads showing the arrangement of the dies and their adjusting 55 mechanism. Fig. 6 is a longitudinal sec-

tional view of the right hand head. Fig. 7 is a transverse section showing the vise which is arranged on the frame, between the heads, and which may be used as a cutter. Fig. 8 is a detail view showing the cutters 60 which may be substituted in lieu of the gripping dies shown in Fig. 7.

In the drawings, 10 designates the machine frame which is supported by legs 11, said legs being connected by a plurality of 65 angle bars 12 which support shelves on which tools may be placed. The frame 10 is formed on either side with a rack 14 on which the heads which will be hereinafter described are arranged to travel.

70 The heads are provided with rotary cutters which may be driven by hand or by power. These cutters are driven by the shafts 15 and 16 which are disposed longitudinally of the machine frame 10 and supported by the ends of said frame in bearings 17. The shaft 15 is provided adjacent both of its ends with a pinion 18 which is splined on the shaft and may be moved longitudinally of the same.

75 Normally these 80 pinions mesh with the rotary cutters of the head and rotate both of the same to form right or left hand threads as the case may be. The driven shaft 16 is provided to change the direction of rotation of either 85

of the cutters. In carrying out this form of drive, the gear 19 is splined on the normally idle shaft 16, this gear 19 being of a width about twice as great as the width of the gears 18. The rotary cutter with which 90

each head is provided includes a gear wheel 20 which is arranged to mesh with the gears 18. When these gears are in mesh with the gears 20 the cutters will each be driven in the same direction cutting the threads on 95

the stock either both right hand or both left hand according to the direction in which the shaft is driven. When it is desired to drive one of the cutters in a direction the reverse of the other to form a left hand 100

thread on one end of the stock and a right hand thread on the other, the gear 18 adjacent the cutter, the direction of rotation of which it is desired to change, is moved out of mesh with the gear 20 of the cutter 105 and into mesh with the gear 19 which is splined on the shaft 16, the gear 19 being moved to a point where the same meshes with the gear 18 and the gear 20. The gear 18 thus transmits movement to the gear 19 110

which is in mesh with the gear 20 driving said gear in a direction reverse to that in which the shaft 15 would normally impart movement to the gear 18. Thus either of the cutters may be reversed in their movement by the manipulation of the gears 18 and 19.

The heads differ in construction, the head 21 at the left of the machine being arranged to move longitudinally of the machine frame to accommodate various lengths of stock and to thread the stock at different points. This head is illustrated in Figs. 5 and 6 and consists of a casing 22 which is formed with a tubular extension 24 which supports the stock. This extension receives the sleeve 25 of a cutter head which is housed by the circular casing 22. This sleeve which is double diameterd is provided with a flange 27 to which is bolted the gear 20 (this construction being common in both right and left hand heads the two heads differentiating more particularly in the mechanism by which the same are slid longitudinally of the machine frame). The cutting mechanism consists of three lugs 29, which are offset from and have their terminals bolted to the gear 20. The plate or annular member 28 is held by the lugs 29 for oscillation, and is provided with the plate or flange 32 which is further provided with the four cam grooves 30. The annular member 28 is formed with the exterior flange 31' at one end, and this forms the means whereby the annular member is properly held against outward movement by the lugs 29. The cutters 33 are mounted between the outer end of the sleeve 25 and the inner face of the plate or flange 32 within the annular member 28, each cutting member being provided with a pin 35 which extends outwardly into its respective cam groove 30. A lever 36 is connected to the annular member 28, so that when said lever is operated to oscillate the member 28, the cutting members 33 are projected into work engaging position or retracted therefrom.

The left hand cutter head is designed as before stated to move longitudinally of the machine frame. This feeding of the cutter head on said frame is accomplished by means of the pinions 40 which are mounted on the shaft 41, said shaft being supported by the bearings 42 of the left hand head 21, the pinions 40 engaging the racks 14 of the machine frame. The shaft 41 is manipulated by the lever 43 said shaft being rotated, to feed the heads longitudinally of the machine frame, this construction being illustrated in detail in Fig. 4 of the drawing.

The right hand head 44 is arranged for a slight movement longitudinally of the frame for the purpose of adjustment, and in this connection attention is called to Fig. 6 of the drawing. A shaft 45 passes trans-

versely through the right hand head, said shaft being supported by bearings 46 in the same manner as the shaft 41 on which the pinions 40 of the left hand head is supported. A plurality of gears 47 are arranged on this shaft 45, to mesh with the racks 14 of the machine frame. When it is desired to move the head 44 longitudinally of the machine the shaft 45 is rotated, the gears 47 feeding the head along the frame.

The vise 49 illustrated in detail in Fig. 7 of the drawing consists of the frame 50 the base of which is provided with flanges 51 which extend beneath the rack 14. The vertically disposed bearings 52 of said frame support a shaft 53 which is provided with the right and left hand threaded portions 54 and 55, the jaws being moved transversely of the machine frame, to contact with the stock by the rotation of the shaft 53. When the vise is used merely as a work support, to support the work between the cutter heads, the gripping dies 58 are supported by the jaws 56 and 57. When the vise is used as a cutting member the rotary cutter shown in detail in Fig. 8 of the drawings is substituted for the dies 58.

The drive shaft 15 is provided at a point adjacent the right hand side of the frame with a worm gear 60 which is arranged to mesh with the worm 61 mounted on the shaft 62 which is supported by the right hand head which is provided with bearings 63 which support the same. The shaft 15 is driven by means of the shaft 62 or the same may project as shown in Figs. 1 and 2 of the drawings from the right hand end of the machine and be rotated by a crank or by power. When the shaft 16 is driven through the medium of the shaft 62, the shaft 62 is either provided with a pulley 64 arranged on the terminal 65 of the shaft or a crank may be attached to the terminal 66 of the shaft. It will be noted that as the shaft 62 is rotated the same will drive the shaft 16 through the medium of the worm gear 60 and the worm 61 arranged on the shaft 62.

The many advantages of a machine of this character will be clearly apparent as it will be noted that the same with slight adjustment, may be arranged to cut threads in either direction on both ends of the stock and that the stock may be threaded at any point throughout its length, the same being supported intermediate the cutting members by a work support which may be converted into a cutting member.

What is claimed is:—

A thread cutter including a plurality of rotary cutters, a drive shaft and a driven shaft disposed in parallel relation, pinions splined on the drive shaft, a pinion splined on the driven shaft, a gear carried by each of the cutters, the pinion of the drive shaft

when in engagement with said gears driving the same in one direction, the pinion of the driven shaft being disposed to mesh with either of the other pinions, and the gear of an adjacent cutter to reverse the movement of the same.

In testimony that I claim the foregoing as

my own, I have hereto affixed my signature in the presence of two witnesses.

EDWARD RILEY.

Witnesses:

Wm. C. POWELL,
H. E. RATZLAFF.
